UNITED STATES PATENT OFFICE

2,638,902

BOOK AND BINDER THEREFOR

Charles Edward Emmer, Chicago, Ill., assignor to
 General Binding Corporation, Chicago, Ill., a
 corporation of Illinois

Application October 25, 1947, Serial No. 782,063

1 Claim. (Cl. 129—1)

1

My invention relates to binders and more particularly to an improved binder construction for holding a plurality of sheets to form a book or the like.

One type of binder for holding sheets of paper or the like to form a book or folder comprises a backbone from which a plurality of spaced resilient curved fingers extend. The fingers are curved to define a loop in conjunction with the backbone and are received in suitable aligned holes along one edge of the sheets to be bound. While this method of binding is relatively inexpensive, and provides a neat, attractive appearance, it is subject to the disadvantage that the fingers tend to open when the sheets are pulled relative thereto and may then permit sheets to leak out. Moreover, with this type of binder, assembly of the binder and the sheets is rendered difficult by the fact that the fingers naturally assume a curved shape capable of receiving only a small thickness of sheets at a time, thereby requiring several lifts of small numbers of sheets to build up the desired total thickness of the book.

In accordance with the present invention, an improved binder having a backbone and a plurality of curved fingers is provided in which the fingers are bent inwardly of the loop defined by the backbone and fingers. This inwardly extending portion is relatively straight and acts as a hook to catch the sheets of the folder or book when pulled relative to each other, thereby holding the unit in assembled shape even though pulled in such a manner as otherwise to permit the sheets to leak out. Moreover, when the curved fingers are unwound by suitable binder-opening equipment for the insertion of sheets thereon, the straight portions of the fingers form posts to receive a large number of assembled punched sheets, thereby facilitating and speeding up assembly of the unit by requiring only a single lift during the binding process.

It is accordingly a general object of the present invention to provide an improved book and binder therefor, the binder being of the type having a backbone and a plurality of curled fingers.

Further, it is an object of the present invention to provide an improved binder of the type having a backbone and a plurality of curled fingers wherein the sheets cannot leak out when pulled relative to each other.

Still another object of the present invention is to provide an improved binder having curled fingers operable in the unwound condition to form posts to receive sheets to be bound.

Another object of the present invention is to provide an improved binder finger for use in

2

binders wherein sheets are held by curved fingers and which is shaped to define a hook when pulled by pressure exerted by the sheets.

The novel features which I believe to be characteristic of my invention are set forth with particularity in the appended claims. My invention itself, however, both as to its organization and method of operation, together with further objects and advantages thereof, may best be understood by references to the following description taken in connection with the accompanying drawings.

On the drawings:

Figure 1 is an end elevational view of one form of binder constructed in accordance with the principles of the present invention and containing sheets of paper or the like to form a folder or book;

Figures 2 and 3 are top plan and rear elevational views, respectively, of the structure of Figure 1;

Figure 4 is a view like Figure 2 but without the sheets in place;

Figure 5 is a side elevational view of the binder of Figure 4 with the fingers unwound to show how they form posts over which the sheets to be bound may be inserted;

Figure 6 is a side elevational view showing how the binder of the present invention forms hooks to hold the sheets in position when the sheets are pulled relative to each other.

Figures 7 and 8 are end elevation and top plan views respectively of an alternative embodiment of the present invention with a plurality of sheets bound to form a book; and

Figures 9, 10 and 11 are end elevational, top plan, and side elevational views respectively of still another embodiment of the present invention but without sheets bound therein.

As shown on the drawings:

The book or folder of Figures 1, 2, and 3 comprises a plurality of sheets 10 which may be of paper or similar material and which are punched to define a plurality of spaced rectangular openings 12 along one edge thereof. The binder, indicated generally at 14, consists of an arcuate backbone 16 from which extends a plurality of curled fingers 18, the fingers 18 extending in a direction normal to the axis of the backbone 16 and being in spaced relationship along that axis

to form an array of substantially equally spaced fingers. Each finger 18 defines a loop in conjunction with the backbone 16 so that the entire binder assemblage is of cylindrical shape, the backbone and fingers forming arcuate portions thereof. Each finger 18 is received in an open-

ing 12 punched in the sheets 10, the shape of the opening being made rectangular to correspond with the cross section of the fingers.

The binder 14 is composed of self sustaining sheet like material with sufficient resiliency, at least in the curled fingers 18 thereof, to reclaim a closed loop position even after repeated flexing. Plastics, springy sheet metal and the like are satisfactory.

In accordance with the present invention, the end of each finger 18 is bent inwardly of the loop formed in conjunction with the backbone 16 to form an inwardly extending portion 22, Figure 1. This portion is preferably at least as long as the maximum thickness of the stack of sheets 10 intended to be bound by the binder and extends in a straight line. This portion forms a straight upstanding post for receiving a stack of sheets to be bound, which stack is of thickness equal to or slightly less than the length of the portion 22. As will be described in further detail hereafter, this extending portion 22 also forms a hooked barrier to prevent leakage of the sheets 10 when the sheets are pulled relative to each other. The straight end portions 22 of the fingers 18 are preferably directed inwardly at a right angle or less to the ends of the looped portions of the fingers, as is best seen in the view of Figure 1. In order to best cooperate with the looped finger portions, these ends 22 should not be in obtuse angular relationship with the curled fingers. Such obtuse angular relationship will decrease the effectiveness of the retaining hook properties of the ends 22 but in any event the ends irrespective of their angular relationship with the curled finger portions will have some effectiveness.

The edge of backbone 16 opposite the edge from which the fingers 18 extend is notched at spaced intervals to define the openings 20 into which the fingers 18 extend to close the loop formed by the arcuate backbone 16 without at the same time physically engaging the backbone 16. This portion of the structure is best seen in the views of Figures 2 and 4 which show clearly the space between the bottoms of the notches 20 and the fingers 18 at the points where the latter bend inwardly.

The appearance of the binder 14 when no sheets are mounted thereon will be evident from the view of Figure 4.

Figure 5 is a side elevational view showing how the sheets 10 may be inserted in the binder of Figures 1 to 4. As indicated, a pair of pins 24 and 26 rest against the backbone 16 and the fingers 18 respectively. These pins are pulled to spaced positions relative to each other to unwind or open the fingers 18, this operation being accomplished by a machine provided for this purpose such as, for example, that disclosed and claimed in my pending application Serial No. 733,578, filed March 10, 1947. As is evident from Figure 5, the straight portions 22 of the fingers 18, have no strain placed thereon by the pins 24 and 26, maintain their straight configurations as the fingers are unwound and rotate from the downwardly extending position of Figure 1 to a more nearly upwardly extending position of Figure 5. These portions of the fingers thus form upstanding posts or pins to receive the sheets.

When the sheets 10 have been inserted on the portions 22 of the fingers 18, the binder may be released to cause the fingers to curl to the position of Figure 1. When this takes place, the fingers slide within the opening 12 of the sheets

10 to free the straight portions 22 of the fingers to cause these portions to extend inwardly within the loop formed by each finger in conjunction with the binder, and to cause the sheets 10 to rest about the curved portions of the fingers 18.

Since the binding operation can most economically be carried out by inserting the whole book at one time, the ability of the fingers 18 to receive the desired number of sheets in the aligned condition they naturally assume immediately after punching substantially simplifies and speeds up the process of assembling a book or folder using the binder of the present invention.

Figure 6 is a side elevational view showing how the fingers of the binder of the present invention define hooks to hold the sheets 10 to prevent them from being pulled free of the binder. In this view, the sheets 10 are divided into two portions 10a and 10b which are pulled to spaced positions relative to each other in a manner naturally tending to unwind the fingers 18 and cause the sheets to slide free of the binder. This unwinds the fingers 18, but, since the portions 22 thereof open to a hook-shaped configuration, the tendency of the teeth 18 to unwind further is overcome by the tendency of the portions 22 thereof to form a hook to prevent further opening.

Figures 7 and 8 are side elevation and top plan views respectively of an alternative embodiment of the present invention. As will be evident from these figures, the binder 11 includes a backbone portion 16 from which a plurality of curved fingers 18 extend in like manner as in the embodiment of Figures 1 to 4. Moreover, the ends of the fingers 18 extend inwardly along straight portions 22 to define a hook portion to prevent leakage of the sheets 10 in like manner as in the case of the embodiment of Figures 1 to 4.

The embodiment of Figures 7 and 8 differs from the structure of Figures 1 to 4 in that the edge of the backbone 16 opposite that from which the fingers 18 extend has no notches 20. Instead, each finger is curved inwardly at a point spaced from that edge of the backbone 16 as indicated in the figures, thus defining a loop in conjunction with the backbone, the loop having an opening between the inwardly extending portion of each finger and the edge of the backbone 16.

Figures 9, 10, and 11 are end elevation, top plan, and side elevational views respectively of still another embodiment of the present invention. As will be evident from these figures, the binder 14 includes a backbone portion 16 having a flat portion 16a and opposed bent up edge portions, the curved fingers 18 extending from one of these edge portions to define loops in conjunction with the backbone 16. The ends of the fingers 14 are bent inwardly from a point spaced from the edge of the backbone 16 (see Figure 9) and in direction parallel to the flat portion 16a of the backbone.

The inwardly bent portions 22 of the fingers 18 of the binder of Figures 9 to 11 act in like manner as the fingers 18 of the binder of Figures 1 to 6 to form a hook to hold the sheets against leakage when pulled and to define upstanding posts or fingers upon which the sheets may be mounted when the binder is opened by flexing the fingers to the unwound position.

As indicated above the binder of the present invention may be made of any one of a variety of materials. Preferably, however, it is made of a thermoplastic resin sheet of the type that

may be stamped out to form the developed shape of the binder and then curved under heat to form and set in the desired shape. Upon subsequent cooling, the backbone 16 and the fingers 18 naturally tend, in the released condition, to assume the desired binder configuration and resiliently oppose bending of flexure from this condition such as, for example, upon opening of the binder to receive the sheets. This material possesses the advantages of low cost and the ability to take attractive colors to provide effective bindings.

It will be apparent to those skilled in the art that while I have shown the fingers 18 bent inwardly at points spaced from the edge of the backbone 16, these may, if desired, contact this edge to form a completely closed loop.

While I have shown particular embodiments of my invention, it will, of course, be understood that I do not wish to be limited thereto, since many modifications both in the elements employed and their cooperative combination may be made without departing from the spirit and scope of my invention. I, of course, contemplate by the appended claims to cover any such modifications as fall within the true spirit and scope of my invention.

What I claim as new and desire to secure by Letters Patent in the United States is:

A binder, for securing together a plurality of

5

10

15

20
